SHOE PRESSING MACHINE

Charles K. Woodman, Beverly, Mass., assignor to
 United Shoe Machinery Corporation, Flemington, N. J., a corporation of New Jersey

Application June 16, 1949, Serial No. 99,391

12 Claims. (Cl. 12—51)

1

This invention relates to machines for applying pressure to a lasted shoe to shape or conform the toe portion of the upper to the last and, more particularly, to a machine which may be employed in sequence with the usual toe or bed lasting operation to clamp and hold the upper materials, after they have been lasted, against the feather and rib of a welt type insole positioned on the last.

In the manufacture of welt shoes, the usual method of properly shaping the toe end of a pulled-over upper is first to subject it to the action of heat and vapor to condition the materials so that they may be readily worked. The shoe is then placed in a toe lasting machine where a set of wipers conform the upper, at the toe, to the contours of the last and work the upper materials in over the feather and against the upstanding rib of the insole. Next, it is necessary, in some way, to hold these materials in this desired shape until they have acquired a permanent set so that there is no longer any tendency for them to pull away from the insole rib, or to loosen up about the toe end of the last. While this may be done by the continued application of pressure in the toe lasting machine, the minimum time dwell for the upper to dry sufficiently, so as to inherently maintain its lasted position, is so long, possibly in the neighborhood of three to five minutes depending upon the characteristics of the materials and their vapor content, as to prohibit such practice. It has, therefore, been customary to apply a binding wire to the upper materials, before they are released from the lasting machine, in order that, after removal of the shoe, the materials will be maintained in the desired shape until stitched in position by the subsequent operation of the inseam machine. The operation of anchoring the binding wire about the toe portion with two upstanding tacks driven one on each side and just back of the tip line consumes considerable time during which the machine must remain idle. In addition, after the upper has set, further time and labor must be expended in removing this temporary binding wire which, if not removed before the inseaming operation, might damage the needle and cause consequential delay. In order to avoid the extra time and labor involved in this procedure, and also to expedite the lasting operation by making the toe lasting machine immediately available after a shoe has been lasted, it has been proposed in accordance with a novel method disclosed and claimed in United States Letters Patent No. 2,373,-

2

Arthur L. Russell, to provide an auxiliary pressing apparatus to which the shoe may be transferred from the toe lasting machine.

Accordingly it is a primary object of this invention to provide a novel and improved auxiliary pressing machine, the employment of which will permit the removal of a shoe from a lasting machine as soon as the toe portion has been conformed into lasted position, and which will obviate the installation and removal of any temporary toe binding attachment. To this end my novel machine is designed and particularly adapted for use in advantageously carrying out the method of lasting shoes as described and claimed in the aforementioned patent.

A further object of the invention is to provide an auxiliary pressing machine, adapted to be positioned in proximity with the usual toe lasting machine, and having novel means for applying heat and pressure to the upper materials, around the toe of a shoe, which have previously been lasted so as to hold the upper materials in the desired shape and relationship until they assume an inherent set in the lasted position. More particularly, the pressing means comprises an articulated wiper, or wiper-presser, which is arranged to embrace the toe end of a lasted shoe in such a way as to clamp the lasting margin of the upper materials to the feather and rib of an insole in lasted position. Preferably, this wiper-presser is heated to facilitate the setting of the upper materials into lasted position.

Another object of the invention is to provide novel mechanism for operating the machine with as little as possible expenditure of effort and care on the part of the operator. To this end the machine is provided with a novel arrangement of levers and shifting fulcra whereby an operator, by the continued movement of a single control member, may first rapidly and accurately position the shoe, relatively to the wiper-presser, then clamp the wiper-presser about the upper materials at the toe end of the shoe and press them firmly against the insole rib, and finally, force the shoe heightwise against the wiper-presser to press the upper materials against the feather of the insole.

The above and other objects and features of the invention will be more readily understood from the following detailed description, when considered in connection with the accompanying drawings, and will be pointed out in the appended claims.

Fig. 1 is a view in side elevation of a machine embodying the features of this invention;

Fig. 2 is a view in front elevation of the machine shown in Fig. 1, partly broken away and on an enlarged scale, showing the pressing, heating and toe support elements;

Fig. 3 is a top plan view of the machine, partly broken away, showing the position of the pressing member when a shoe is first presented to the machine;

Fig. 4 is a view of the pressing member partly in horizontal section taken on the line IV—IV of Fig. 2, and viewed in the direction of the arrows;

Fig. 5 is a horizontal view showing further details of the pressing mechanism;

Fig. 6 is a side view of the machine partly broken away and in vertical section taken on the line VI—VI of Fig. 2 and looking in the direction of the arrows;

Fig. 7 is a fragmentary rear elevation view showing a detail of Fig. 6;

Fig. 8 is a vertical section similar to that of Fig. 6, but showing the relative position of parts during a subsequent phase of operation;

Fig. 9 is a vertical section view of a detail taken on the line IX—IX of Fig. 8 and looking in the direction of the arrows;

Fig. 10 is a perspective view showing certain elements of the machine;

Fig. 11 is a top plan view of the machine partly broken away showing the position of the pressing mechanism after clamping a shoe;

Fig. 12 is a view similar to that of Fig. 8, but showing the position of respective parts during another phase of operation which corresponds to the phase shown in Fig. 11; and

Fig. 13 is an enlarged fragmentary view drawn in perspective to show a detail of Fig. 2.

In order to better understand the invention and drawings, a brief description will first be given of the principal parts of the machine with respect to their modes of operation. These parts comprise a set of horizontally curved articulated wiper-pressers, shown in detail by Fig. 4 and designated in general as W, for pressing and clamping the lasting margin of an upper against the feather and rib of an insole; a vertical yieldable hold-down 90 engageable with the insole to position the shoe for the pressing operation; a vertically movable toe support 84 for jacking the shoe and securely clamping it first against the hold-down and then against the wiper-pressers; and an arrangement of levers and linkages, all controlled by a single treadle 26, for progressively and alternately actuating the toe support and wiper-pressers during the various operational phases of the machine.

Before any downward pressure is applied to the treadle, the position of the various elements is depicted by Fig. 6, and may be termed the idle phase, during which the toe support and hold-down are both in their lowermost positions, and the pressing elements are withdrawn with their articulated jaws opened to the full extent for receiving a shoe. Prior to operating the machine, a shoe will be removed from an adjacent lasting machine and will be immediately placed by the operator with the insole positioned upwardly in contact with the hold-down.

To commence the second phase, depicted by Fig. 8, which may be termed the quick take-up jacking operation, the treadle is partially depressed to elevate the toe support rapidly until it presses against the shoe S, as shown in Fig. 12,

with sufficient force to maintain the insole I against the hold-down 90. Up to this point the heated pressing elements, restrained by a series of springs, have remained in their idle position.

5 A further depressing of the treadle commences the third or wiping phase during which the shoe remains stationary between the hold-down and toe support while the wiper-pressers slide horizontally forward until they abut the toe point of the shoe; then the articulated jaws commence closing to wipe and press the upper materials, as shown in Fig. 11, against the feather and rib of the insole.

When the maximum effective pressure has 15 been applied for thus clenching the heated presser members inwards against the upper material, the final phase of operation is commenced, during which the remaining downward movement of the treadle transmits a force through a powerful leverage to drive the toe support, shoe and yieldable hold-down still higher so that the lasting margin is forcefully clamped upwards against the bottom edges of the heated pressing member.

Throughout the various phases of operation 20 the progressive downward movement of the treadle is held locked against recession, so that the full pressure applied to the shoe may be maintained as long as desirable. When the upper materials have set sufficiently, the shoe 25 is released by pressing a release treadle 28 which allows the various parts of the machine to return to their idle position.

The detailed construction and operation of the machine will now be described, first with particular reference to the relationship of parts during the idle position as shown in Figs. 1 through 7. The framework, to which the parts are attached, comprises a hollow pedestal portion 20 extending upwardly from the floor to support a head housing 22 within the forward part of which are contained the hold-down 90, the toe support 84 with its jacking assembly, and the articulated wiper-pressers which are movably supported within the housing upon a pair 30 of brackets 23, Figs. 2 and 13, each provided with guide grooves 172 for receiving a portion of the presser assembly. A stud 24 extending horizontally from the base of the pedestal provides a pivotal mounting for both the treadle 26 for applying pressure to the shoe and a release treadle 28 for tripping a locking mechanism to permit all parts to be returned to their idle position by the combined force of a series of biasing springs, the locations and functions of which 35 will be pointed out in detail later on. A pull rod 30 pivotally connected at one end to the treadle 26 extends upwardly through the frame pedestal and is connected at its upper extremity by a pin 32 passing through the lower ends 40 of a bifurcated casing 34 formed on the lower portion of a vertical control rod 36 extending upwards into the head housing. Within the casing 34 are two adjacent pawl members 38 and 40 each having transverse ratchet teeth 45 terminally formed on its upper forward face for coacting with a rack of transverse teeth 42 affixed to the framework of the pedestal 20. Each pawl is mounted at its lower end upon a pivot pin 44 passing transversely through the 50 casing 34 and running outwardly through vertical guide slots formed through two ears 46 extending rearwardly from the pedestal. Two springs 48, attached at their upper ends to the framework and at their lower ends to the extremities of the pin 44, resiliently urge the cas- 55

ing and control rod 36 upwards. Two springs 50, each attached to one of the pawls, normally urge them forwardly and into engagement with the ratchet rack 42. The lower end of the pawl 40 is provided with a bell crank arm 52 to which is attached a pull rod 54 connecting with the release treadle 28 so that when this treadle is pressed downwardly the pawl 40 is pivoted rearwardly out of engagement with the teeth 42. The pawl 38, while not connected directly with the release mechanism, is also carried rearwardly by a transverse stud 56 affixed thereto and extending behind and adjacent the pawl 40 and through guide slots in the sides of the casting 34.

The upper extremity of the control rod 36 is forked to straddle a horizontal control lever 58 to which it is medially linked by a pivot pin 60. The rear arm of the lever 58 is in turn connected by a pivot 62 to a tie rod 64 which is restrained against downward movement by the force of a spring 66. The upper end of the rod 64 is connected by a pivot pin 68 to two spanning arms 70 and 72 forming a toggle lever for providing horizontal movement to the wiper-presser mechanism. In addition to the restraining action of the spring 66, this toggle lever is restrained against being extended laterally by the force of two springs 74 tending to draw the outward ends of the arms 70 and 72 together and to hold the rod 64 and pivot 62 in an elevated position. The forward arm of the lever 58 is linked to a vertical tie rod 76 by a pivot 78 which is slidably positioned on the frame by the vertical guide slots 80. A downward movement of the control rod 36 will transmit through the lever 58 concomitant downward forces on the tie rods 64 and 76. However, the above-described restraining force of the springs 66 and 74 will at first be sufficient to overcome the downward pull on the rod 64, causing a fulcrum for the lever 58 to be established at the pivot 62, so that the toe support jacking mechanism will be actuated by the resultant downward movement of the tie rod 76 connected by a pin 77 to one end of the variable leverage bars 62 which act as a jacking lever.

The toe support 84, its thrust rod 86 and a flexible hinge linkage 88 (Figs. 2 and 10) are progressively actuated by the jacking lever 82 which alternately pivots upon two fulcra. The initial downward movement of the pin 77 commences the quick take-up jacking phase (Figs. 8, 9 and 10) during which there is little resistance to the upward travel of the toe support and a short arm leverage is sufficient to rapidly clamp the shoe in contact with the holdown 90. A fulcrum rod assembly 92 is resiliently supported against downward movement by a loaded compression spring 94 the force of which may be adjusted by a hand nut 96 threaded to the rod 92 within a barrel 98 which in turn is upwardly supported upon the framework by two laterally extending trunnions 100 providing for angular adjustment of the fulcrum rod 92. As the treadle depresses the point 77 the forward end of the lever 82 moves upward raising both the toe support and an auxiliary fulcrum rod 102 whose downward recession is prevented by a detent pawl 104 held by a spring 106 into engagement with a rack of transverse ratchet teeth 108 formed on the rod 102. The mechanism controlling the engagement and disengagement of this pawl with the auxiliary fulcrum is selectively operated by the movement of the vertical

10

tie rod 76 as will be explained later. When the shoe insole I (Fig. 12) is clamped upwardly against the holdown 90, which is held down by a heavy compression spring 112, resistance to further movement of the jacking mechanism is sufficient to overcome the combined force of the springs which up to this point have acted to restrain the operation of the wiping and pressing mechanism. Now the control lever 58 commences to fulcrum on the pivot 78 drawing the tie rod 64 downwardly thereby spreading the toggle arms 70 and 72 to initiate the wiping phase of operation.

Since the foot of the arm 70 is fastened by a pin 116 to a relatively fixed slide 118 horizontally positioned on the framework by an adjustment nut 120, the resultant horizontal movement of the spreading arms will be confined to the forward advance of a slide 114 attached to the foot of the arm 72 by a pin 122.

As hereinafter explained in detail, it is this movement of the slide 114 which activates the wiper-presser assembly, first to move it bodily forward into contact with the materials of the lasting margin, and then to cause the articulated jaws to move inwardly over the feather to wipe the materials and press them inward against the insole rib.

Referring now to the illustrated construction 30 of the toe wiping and pressing assembly, and viewing more particularly Figs. 2 through 5, it will be seen that the unit which operatively contacts the lasting margin is a flexible U-shaped band comprised of several variously shaped rigid blocks, each arranged in series formation, and held in close articulated association with adjacent blocks of the series so that by their relative movement the band may readily accommodate itself to the shape and position of the toe portion 35 of the last to automatically and uniformly conform to the size and swing of said toe portion. Each block is "strung" on a tightly coiled spring 124 through the core of which passes a wire cable 126 the two ends of which are secured by stop collars 128. The central block 130 is substantially in the form of a circular disk having a rearwardly extending boss 134 and a diametrically opposite small concaved edge portion 136 engageable with the tip point of a shoe. This block is pivotally anchored to the assembly by a pin 132 extending vertically from the top and bottom of the block. On either side of this central block are a number of crescent-shaped blocks 138, the jointed curved faces of 40 which permit articular movement while remaining in engagement with one another. It is to be noted that the bore, of the passageway through the central blocks, is flared outwardly to prevent the spring and cable core from restricting said articular movement. The flexible U-shaped series terminates at both ends in elongated curved end blocks 140 provided with an insert sleeve 142 abutting against the stop collars 128 for adjusting the tension of the cable. Each end block 140 has an outwardly extending ear 144 45 pivotally connected to the forward end of thrust arms 146 which in turn are attached at their rearward extremities, by pivots 148, to a cross-piece 150 secured transversely to the forward end of the slide 114. The articulated series of blocks is confined against heightwise displacement by two pairs of curved rigid arm plates 152, centrally anchored together and to the assembly in hinged relationship by the pin 132, forming two 50 sets of U-shaped supports, one above and the

other below the blocks and each substantially co-extensive with and contiguously adjacent to the series of jointed blocks. The adjacent forward ends of the plates 152 are slidably linked to an end block 140 by a pin 154 set in the block and extending through slots 156 formed in the plates. Thus the arm plates maintain a guiding contact above and below the blocks without impairing the horizontal movement necessary to operatively position the several blocks.

The crosspiece 150 is provided with two pins 158 each extending forwardly through helical compression springs 160 which form yieldable thrusts for a transverse yoke piece 162 slidably journaled on the forward part of each pin and held thereon by retaining washers and cotter pins. The forward face of the yoke 162 is bifurcated forming two fingers 164 which extend forward and are engageable with the rear edges of the three centralmost blocks of the series to yieldingly press them against the tip point of the shoe. The U-shaped series of blocks and their guide plates 152 are sandwiched between an upper carrier plate 166 and a lower plate 168. These carrier plates are secured together in spaced apart relation to one another by screws 170, and are pivotally secured to the central block 130 and guide plates 152 by the vertical pin 132, so that the entire pressing assembly is movable together lengthwise of the shoe, and is supported in the head housing 22 by the lateral edges of the upper plate 166 sliding along longitudinal guideways 172 formed in the bracket pieces 23 affixed to the framework (Figs. 12 and 13).

The wiper-presser assembly is heated by a thermostatically controlled electric unit 173, attached to the underside of the carrier plate 168, having a heat control element 174 and a heater 176 both joined by conduits to a regulator outlet box 177.

When the slide 114 and crosspiece 150 are first actuated by the foot treadle, the wiper-presser assembly is moved forward bodily both by the thrust arms 146, and by the thrust springs 160 acting upon the yoke 162 until the central block 130, carrying the pin 132, strikes the point of the toe. When this block 130 is thus prevented by the shoe from continuing forward, the pin 132 acts as an anchor or stationary pivot for all the elements connected thereto. Since all direct bodily forward movement has thus been arrested, the continued forward pressure applied upon the thrust arms 146 by the crosspiece 150 tensions and forces the articulated series of 55 blocks inward widthwise of the shoe, Fig. 11. During this final movement of the articulated blocks, the fingers 164 are forced with increasing pressure, exerted by the yieldable thrust springs 160, against the central blocks to cause them to draw the lasting margin tightly over the featherline and press it forcefully up against the insole rib.

It is to be noted that the peripheral edges of the holdown member 90 are preferably so designed that when the shoe is placed thereagainst by the operator the holdown will fit within and contiguously adjacent to the inner wall of the rib forming a rigid lateral support to prevent any extreme pressures from crushing the rib inwards beyond its proper position on the insole. Thus when the entire toe portion of the lasting margin has been firmly clenched inwards against the nonyielding rib, further actuation of the presser assembly is precluded.

Now, as the treadle 26 continues to exert increasing downward pull upon the lever 58, a force of great magnitude is applied upwardly upon the thrust rod 86 by the jacking lever 82 which is now pivoting on the auxiliary fulcrum rod 102 producing a far greater mechanical advantage than was previously obtainable with the fulcrum rod 92. This force, transmitted upwards by the insole 1 to the holdown 90, is sufficient to overcome the resistance of the spring 112 which now yields with the holdown to permit the shoe to be forcefully jacked upwards and clamped by the toe support, so that the lasting margin is jammed upwards against the heated pressing member to form a well defined edge about the toe portion of the shoe.

The detent assembly, Fig. 7, on the foot of the control rod 36 enables the pressure upon the toe portion to be maintained as long as desirable. When the upper materials have attained an inherent set the operator may release the shoe by 20 pressing the release treadle 28. This trips the pawls 38 and 40 to allow the series of biasing springs to return the operative parts of the machine to their idle positions. First, the rods 36 and 64 are elevated by the springs 48 and 66 relieving the downward tension upon the tie rod 64 so that the cross bar 150 may be retracted by the springs 74. Now the presser assembly, thus relieved of all forward thrust, is withdrawn from the shoe by a pull rod 180 which is urged rearwards by a compression spring 178. As the control rod 36 returns to its idle position, the lever 58 draws the tie rod 76 upwards to elevate the rearward end of the leverage bars 82 and commence lowering the toe support thrust rod 86. During the ascent of the tie rod 76 a detent tripping pin 184 laterally affixed to the rod, engages with and elevates the rear arm of a lever 186 which is pivotally attached to the framework by a fixed pin 182 and movably linked at its forward end to a bell crank arm 188. The resultant downward swing of the arm 188 extends the detent spring 106 and moves the pawl 104 out of engagement with the auxiliary fulcrum rod 102, so that the toe support and jacking mechanism may return to the idle position. It is to be noted (Fig. 10) that the detent tripping pin 184 is vertically adjustable upon the tie rod 76, so that the pawl's engagement with the fulcrum rod 102 may be timed in relation to the downward extent of the operating treadle 26.

While the foregoing operational description of this novel pressing machine has pertained to its employment for pressing the toe of a welt shoe it is to be understood that the invention and appended claims are not to be so limited for it is within the contemplation of this invention to use a similar arrangement of levers and jacking mechanism in conjunction with a wiper pressing assembly to press and clamp the lasting margins of other than welt shoes. For instance, it might be advantageously employed for shaping the end of an upper on a cement type shoe by holding the margin under heat against the insole until the cement has hardened, thus avoiding the installation and removal of the toe wire or upstanding tacks. It might also be employed to attach an upper to an insole by heat activated adhesives applied to the lasting margin and insole edges. The invention also contemplates a similar arrangement for pressing an upper to form a heel seat.

Although in constructing a machine in accordance with this invention it is recommended that

a wiper presser such as herein described be employed the invention is not to be construed as in any way limited to the use of this type of presser because there are various known types or designs of pressing devices which may readily be adapted for suitable operation.

Having thus described my invention what I claim as new and desire to secure by Letters Patent of the United States is:

1. A machine for applying pressure to the lasted margin of a shoe upper on a last comprising, in combination, a member for engaging the bottom of the shoe, a supporting member engageable with the top of the shoe and movable heightwise of the shoe toward the bottom engaging member, a U-shaped pressing member movable in a horizontal plane contiguously parallel to the bottom of the shoe for clamping the lasting margin of the upper against the bottom of the shoe in lasted position, a supporting guideway for the pressing member maintaining it against heightwise movement, and manually operated mechanism including a single progressively activated control member for consecutively moving said supporting and pressing members, in sequence, first to position the bottom of the shoe against the bottom engaging member, next to move horizontally said pressing member over the bottom of the shoe, and finally, to forcefully jack the shoe against said pressing member.

2. A machine for applying pressure to the lasted margin of a shoe upper on a last comprising, in combination, a holddown for engaging the bottom of the shoe, a supporting member engageable with the top of the shoe and movable heightwise of the shoe toward the holddown, a U-shaped pressing member movable in a horizontal plane contiguously parallel to the bottom of the shoe for clamping the lasting margin of the upper against the bottom of the shoe in lasted position, a supporting guideway for the pressing member maintaining it against heightwise movement, and manually operated mechanism including a single progressively activated control member for consecutively moving said supporting member and pressing member, in sequence, first to position the bottom of the shoe against said holddown, next to move horizontally said pressing member over the bottom of the shoe, and finally, to forcefully jack the shoe against said pressing member.

3. A machine for applying pressure to the lasted margin of a shoe upper on a last comprising, in combination, a relatively yieldable holddown for engaging the bottom of the shoe, a supporting member engageable with the top of the shoe and movable heightwise of the shoe toward the holddown, a U-shaped pressing member movable in a horizontal plane contiguously parallel to the bottom of the shoe for clamping the lasting margin of the upper against the bottom of the shoe in lasted position, means for maintaining the pressing member against heightwise movement, and manually operated mechanism including a single progressively activated control member for a consecutively moving said supporting member and pressing member, in sequence, first to position the bottom of the shoe against said holddown, next to move horizontally said pressing member over the bottom of the shoe, against said pressing member and yieldable holddown.

4. A machine for applying pressure to the lasted margin of a shoe upper on a last comprising, in combination, a holddown for engaging

the insole of the shoe and adapted to contact and laterally support the rib of the insole, a toe support engageable with the top of the shoe and movable heightwise of the shoe toward the hold-

5 down, a U-shaped pressing member movable in a horizontal plane contiguously parallel to the bottom of the shoe for clamping the lasting margin of the upper against the feather and rib of the insole in lasted position, means for maintaining the pressing member against heightwise movement, and manually operated mechanism including a single progressively activated control member for consecutively moving said toe support and pressing member, in sequence, first to position the insole against said holddown, next to move horizontally said pressing member inwardly over the insole, and finally, to forcefully jack the shoe against said pressing member to form a well defined feather line.

20 5. A machine for applying pressure to the lasted margin of a shoe upper on a last comprising, in combination, a relatively yieldable holddown for engaging the insole of the shoe and adapted to contact and laterally support the rib

25 of the insole, a toe support engageable with the top of the shoe and movable heightwise of the shoe toward the holddown, a flexible U-shaped pressing member movable lengthwise and widthwise of the shoe in a plane contiguously parallel

30 to the shoe bottom and capable of conforming to the forepart of the shoe for clamping the lasting margin of the upper against the feather and rib of the insole in lasted position, means for maintaining the pressing member against height-

35 wise movement, and manually operated mechanism including a single progressively activated control member for consecutively moving said toe support and pressing member, in sequence, first to position the insole against said holddown, next to move said pressing member lengthwise of the shoe into contact with the lasted margin at the toe point of the shoe, then to forcefully move the pressing member inwardly widthwise over the insole to wipe said margin over the feather and clamp it against the rib of the insole, and finally, to forcefully jack the shoe against said pressing member and yieldable holddown to form a well defined forepart feather line.

6. A machine for applying pressure to the

50 lasted margin of the upper of a welt shoe on a last comprising, in combination, a holddown for engaging the insole of the shoe, a toe support engageable with the top of the shoe and movable heightwise of the shoe toward the holddown,

55 a flexible U-shaped pressing member movable lengthwise and widthwise of the shoe in a plane contiguously parallel to the shoe bottom and capable of conforming to the forepart of the shoe for clamping the lasting margin of the upper

60 against the feather and rib of the insole in lasted position, means for maintaining the pressing member against heightwise movement, and manually operated mechanism including a single progressively activated control member for con-

65 secutively moving said toe support and pressing member, in sequence, first to position the insole against said holddown, next to move said pressing member lengthwise of the shoe into contact with the lasted margin at the toe point of the shoe,

70 then to forcefully move the pressing member inwardly widthwise over the insole to wipe and clamp said margin over the feather and against the rib of the insole, and finally, to forcefully jack the shoe against said pressing member to form a well defined forepart feather line.

7. A machine for applying pressure to the lasted margin of the upper of a welt shoe on a last comprising, in combination, a relatively yieldable holddown for engaging the insole of the shoe, a toe support engageable with the top of the shoe and moveable heightwise of the shoe toward the holddown, a flexible U-shaped pressing member in a plane contiguously parallel to the shoe bottom and capable of conforming to the forepart of the shoe for clamping the lasting margin of the upper against the feather and rib of the insole in lasted position, means for maintaining the pressing member against heightwise movement, and manually operated mechanism including a single progressively activated control member for consecutively moving said toe support and pressing member, in sequence, first to position the insole against said holddown, next to move said pressing member lengthwise of the shoe into contact with the lasting margin at the toe point of the shoe, then to forcefully move the pressing member inwardly widthwise over the insole to wipe and clamp said margin over the feather and against the rib of the insole, and finally, to forcefully jack the shoe against said pressing member and yieldable holddown to form a well defined forepart feather line.

8. A machine for applying pressure to the lasted margin of the upper of a welt shoe on a last comprising, in combination, a member for engaging with the insole of the shoe, a supporting member engageable with the top of the shoe and movable heightwise of the shoe toward the insole engaging member, a heated U-shaped pressing member capable of conforming to the forepart of the shoe and movable in a horizontal plane contiguously parallel to the bottom of the shoe for clamping the lasted margin of the upper over the forepart feather of the insole, a supporting guideway for the pressing member maintaining it against heightwise movement, and manually operated mechanism including a single progressively activated control member for consecutively moving said supporting member and heated pressing member, in sequence, first to position the insole against the insole engaging member, next to move horizontally said pressing member inwardly over the forepart feather of the insole to wipe and clamp said margin over the feather and insole, and finally, to forcefully jack the shoe against said heated pressing member to form a well defined forepart feather line.

9. A machine for applying pressure to the lasted margin about the end of a shoe on a last comprising, in combination, a holdown for engaging the bottom of the shoe, a supporting member engageable with the top of the shoe and movable heightwise of the shoe toward the holdown, a U-shaped pressing member capable of conforming to the end of the shoe for clamping the lasting margin of the upper against the bottom of the shoe in lasted position, and actuating means operable by a single control element for operating said members in timed relation to one another, first to impart to the supporting member an initial rapid movement of considerable extent to position the bottom of the shoe against the holdown, then to impart movement to the pressing member to bring it into pressing contact with the lasted margin, and finally, to impart to said supporting member a slower movement of less extent having increased mechanical advantage to forcefully jack the shoe bottom against the pressing member, said means comprising a control lever medially connected to

10 a source of power, a shoe jacking lever terminally linked to one end of the control lever and medially supported by two spaced-apart alternate fulcrum, fulcrum-selector means for increasing the mechanical advantage of said jacking lever, a third lever linked to the other end of said control lever for operating the pressing member, and biasing means for restraining the operation of said third lever until after the initial rapid movement of the supporting member.

11 10. A machine for applying pressure to the lasted margin about the end of a shoe on a last comprising, in combination, a relatively yieldable holdown for engaging the bottom of the shoe, a supporting member engageable with the top of the shoe and movable heightwise of the shoe toward the holdown, a U-shaped pressing member capable of conforming to the end of the shoe for clamping the lasting margin of the upper against the bottom of the shoe in lasted position, and actuating means operable by a single control element for operating said members and holdown in timed relation to one another, first to impart to the supporting member an initial rapid movement of considerable extent to position the bottom of the shoe against said holdown, then to impart movement to the pressing member to bring it into pressing contact with the lasted margin, and finally, to impart to said supporting member and holdown a slower movement of less extent having increased mechanical advantage to forcefully jack the shoe bottom against the pressing member, said means comprising a control lever medially connected to a source of power, a shoe jacking lever terminally linked to one end of the control lever and medially supported by two spaced-apart alternate fulcrum, fulcrum-selector means for increasing the mechanical advantage of said jacking lever, a third lever linked to the other end of said control lever for operating the pressing member, and biasing means for restraining the operation of said third lever until after the initial rapid movement of the supporting member.

12 11. A machine for applying pressure to the lasted margin about the toe of a welt shoe on a last comprising, in combination, a relatively yieldable holdown for engaging with the insole of the shoe, a toe support engageable with the top of the shoe and movable heightwise of the shoe toward the holdown, a flexible U-shaped pressing member movable lengthwise and widthwise of the shoe and capable of conforming to the forepart of the shoe for clamping the lasting margin of the upper against the feather and rib of the insole in lasted position, and actuating means operable by a single control element for operating said member, toe support and holdown in timed relation to one another, first to impart to the toe support an initial rapid movement of considerable extent to position the insole against said holdown, then to impart movement to the pressing member to bring it into pressing contact with the lasted margin, and finally, to impart to said toe support and holdown a slower movement of less extent having increased mechanical advantage to forcefully jack the shoe bottom against the pressing member, said means comprising a control lever medially connected to a source of power, a shoe jacking lever terminally linked to one end of the control lever and medially supported by two spaced-apart alternate fulcrum, fulcrum-selector means for increasing the mechanical advantage of said jacking lever, a third lever linked to the other end of said control lever for

operating the pressing member, biasing means for restraining the operation of said third lever until after the initial rapid movement of the toe support, and biasing means associated with said holddown for restraining the yielding thereof until after the pressing member has moved lengthwise and widthwise of the shoe.

12. A machine for applying pressure to the lasted margin about the toe of a welt shoe on a last comprising, in combination, an articulated heated pressing member movable lengthwise and widthwise of the shoe for first contacting and then clamping the lasting margin of the upper against the feather and rib of the insole in lasted position, a toe support engageable with the top of the shoe and movable heightwise of the shoe a predetermined distance to operatively position the shoe to receive said pressing member, a relatively yieldable holddown engageable with the bottom of the insole for limiting the initial movement of said toe support, and actuating means operable by a single control element for operating said pressing member, toe support and holddown in timed relation to one another, first to impart to the toe support an initial rapid movement of considerable extent to position the insole against said holddown, then to impart movement to the heated pressing member to bring it into pressing contact with the lasted margin, and finally, to impart to said toe support and holddown a slower

movement of less extent having increased mechanical advantage to forcefully jack the feather portion of the shoe bottom against said pressing member, said means comprising a control lever

5 medially connected to a source of power, a shoe jacking lever terminally linked to one end of the control lever and medially supported by two spaced-apart alternate fulcras, fulcrum-selector means for increasing the mechanical advantage of said jacking lever, a third lever linked to the other end of said control lever for operating the pressing members, biasing means for restraining the operation of said third lever until after the initial rapid movement of the toe support, and biasing means associated with said holddown for restraining the yielding thereof until after the pressing member has moved lengthwise and widthwise of the shoe.

CHARLES K. WOODMAN.
